UNITED STATES PATENT OFFICE.

PHILIP PUBLICKER, OF PHILADELPHIA, PENNSYLVANIA.

DISTILLING APPARATUS.

1,087,907.

Specification of Letters Patent. Patented Feb. 17, 1914.

Application filed December 28, 1911. Serial No. 668,224.

To all whom it may concern:

Be it known that I, PHILIP PUBLICKER, a citizen of the United States, residing at Philadelphia, in the county of Philadelphia and State of Pennsylvania, have invented 5 certain new and useful Improvements in Distilling Apparatus, of which the following is a specification.

My invention relates to improvements in 10 distilling apparatus designed primarily for the recovery of alcohol and ether, and in which a suction pump is employed to draw the vapor rapidly through the system, and increase the efficiency of the apparatus, and 15 secure the maximum of product in the minimum space of time.

With these and other objects in view, the invention consists in certain novel features of construction and combinations and arrangements of parts, as will be more fully hereinafter described and pointed out in the claim.

The accompanying drawing is a view in 20 vertical section illustrating my improvements.

1, 1, represent kettles in which a low grade alcohol is heated by steam coils 2 in the bottom of the kettles. These steam coils are connected with any suitable source of 30 steam supply, are located in the bottom of the kettles, and through which a continuous supply of steam is had to heat the alcohol and cause it to become volatile. The outlet pipes 3 of the kettles are each provided with 35 cocks 4, and are connected to a pipe 5. The cocks 4 enable either or both of the kettles to be in open communication with pipe 5, which directs the vapor into a rectifying column 6. This column 6 is connected by a 40 pipe or goose neck 7 with a coil 8 in a condenser 9, and the lower end of the coil 8 is connected by a pipe 10 with the top of a receptacle 11. The top of this receptacle 11 is connected by a pipe 12 and goose neck 12^a 45 with the lower end of a coil 13 in a condenser 12, and the said coil at its lower end is connected to the top of the receptacle 15 by means of a pipe 16.

A pipe 17 connects with the upper end of 50 coil 13, and extends downwardly and communicates with the top of the receptacle 18. The pipe 17 between its highest point, and the receptacle 18, is provided with an elbow 19 connecting the said pipe with a suction pump 20, and this suction pump 20 is connected at its opposite side to a pipe 21 which

extends down into a receptacle 22, and terminates near the bottom of said receptacle below the level of liquid therein.

The condensers, may of course, be cooled 50 in any way, but they are preferably of the ordinary type containing water or other suitable liquid, which is kept in continuous flow through the condensers, and enters at inlets 23, and escapes at outlets 24. The 55 condenser 9 is preferably at a temperature approximating 70° Fahr. and the condenser 14 is maintained at a temperature approximating 50° Fahr.

When one or both of the cocks 4 are open 60 and suction pump 20 in operation, the vapor rising in the kettles 1 will be drawn upwardly through the rectifying columns 6, thence into the coil 8 in condenser 9, which will cause the more volatile constituent to 65 be condensed and fall into the receptacle 11. This less volatile constituent will be the alcohol, and the more volatile constituent, the ether and aldehyde, will be drawn up through pipe 12 into the coil 13 in condenser 70 14. The more volatile constituent, namely, the ether, will condense and fall into the receptacle 15, while the low grade aldehyde will be drawn through pipe 17 and dropped 75 down the said pipe into receptacle 18. Such 80 vapor as may remain, will be drawn through the suction pump 20, and discharged through pipe 21 into the water in receptacle 22, and be condensed therein, so that there will be 85 no waste to the apparatus. 90

By connecting pipe 16 from tank 15 with the bottom of coil 13, any vapor which may form in tank 15 due to a rise in temperature and the action of the partial vacuum, will be condensed in the coil 13, and fall back 95 into the receptacle, and this liquid will be prevented from passage down pipe 12 because of the goose neck 12^a. The coil 13 therefore operates to prevent any loss from tank 15, because it is interposed between 100 the tank and the suction pump.

It will be noted that by providing a plurality of kettles, that one kettle may be in communication with the apparatus, while the other kettle is cut off, and is being recharged. This enables the process to be carried on continuously, and by reason of the suction or partial vacuum caused throughout the system, the movement of the vapor and the condensation is more rapid, causing 110 the apparatus to produce the maximum of output in the shortest possible space of time.

Various slight changes might be made in the general form and arrangement of parts described without departing from my invention, and hence I do not limit myself to the precise details set forth, but consider myself at liberty to make such changes and alterations as fairly fall within the spirit and scope of the appended claim.

Having thus described my invention, what I claim as new and desire to secure by Letters Patent is:

A distilling apparatus comprising a kettle in which the liquid to be distilled is vaporized, a condenser located in a higher plane than the kettle, a tank located in a lower plane than the condenser, a pipe connecting the kettle and the condenser, a second pipe connecting the condenser and the tank, a second condenser having a sub-merged coil, a third pipe connecting the tank

with the said coil in the second condenser adjacent its lower end and having a goose neck therein between the tank and said last-mentioned condenser, a second tank, a pipe connecting the second tank with the lower end of said coil, a third tank, a pipe connecting the upper end of said coil with the third tank, a suction pump communicating with said last-mentioned pipe, a water column, and a discharge pipe communicating with said pump and projecting into the water column below the liquid level in the latter, substantially as described.

In testimony whereof I have signed my name to this specification in the presence of two subscribing witnesses.

PHILIP PUBLICKER.
